US00D965783S

(12) **United States Design Patent** (10) Patent No.: **US D965,783 S**
(45) Date of Patent: ** Oct. 4, 2022

(54) **KNIFE FOR SURGICAL PURPOSES**

(71) Applicant: **MANI, INC.**, Tochigi (JP)

(72) Inventors: **Hideyuki Kurihara**, Saitama (JP);
Takafumi Doi, Tochigi (JP); **Masayuki**
Watanabe, Tochigi (JP)

(**) Term: **15 Years**

(21) Appl. No.: **35/512,050**

(22) Filed: **Dec. 21, 2020**

(80) **Hague Agreement Data**

Int. Filing Date: **Dec. 21, 2020**

Int. Reg. No.: **DM/212515**

Int. Reg. Date: **Dec. 21, 2020**

Int. Reg. Pub. Date: **Jun. 25, 2021**

(30) **Foreign Application Priority Data**

Jun. 22, 2020 (JP) 2020-012426
Jun. 22, 2020 (JP) 2020-012427

Primary Examiner — Mojtaba Tehrani

(57) **CLAIM**

The ornamental design for a knife for surgical purposes, as shown and described.

DESCRIPTION

1. Knife for surgical purposes

2. Knife for surgical purposes

1.1 : Front

1.2 : Top

1.3 : Bottom

1.4 : Left

1.5 : Right

1.6 : Enlarged left view

1.7 : Enlarged right view

2.1 : Front

2.2 : Top

2.3 : Bottom

2.4 : Left

2.5 : Right

2.6 : Enlarged left view

2.7 : Enlarged right view

Designs 1 and 2: broken lines form no part of the claimed designs; rear views are omitted because they are symmetrical to the front views of each design; the knife of each design has the blade bent at a desired angle with respect to the axial direction of the handle thereof; the tip of the blade of design 1 is gently curved so as to match the shape of an eyeball; the blade of design 2 is gently curved as a whole so as to match the shape of an eyeball.

1 Claim, 14 Drawing Sheets
